(57) **CLAIM**

We claim the ornamental design for a body for a model vehicle, as shown and described.

DESCRIPTION

FIG. 1 is a top, left, front perspective view of a body for a model vehicle;

FIG. 2 is a top plan view thereof;

FIG. 3 is a left side elevation view thereof;

FIG. 4 is a front elevation view thereof; and,

FIG. 5 is a rear elevation view thereof.

The appearance of the right side of the body for a model vehicle is a mirror image of the left side of the body for a model vehicle.
